(57) **CLAIM**

The ornamental design for a stove exhaust system, as shown and described.

DESCRIPTION

FIG. 1 is a top-front-right perspective view of a stove exhaust system showing our new design;

FIG. 2 is a front view thereof;

FIG. 3 is a back view thereof;

FIG. 4 is a right-side view thereof;

FIG. 5 is a left-side view thereof;

FIG. 6 is a top view thereof;

FIG. 7 is a bottom view thereof; and,

FIG. 8 is a top-front-left perspective view thereof.

The broken lines in FIGS. 1-6 and 8 depict portions of the stove exhaust system that form no part of the claimed design.
